UNITED STATES PATENT OFFICE

163,295

RADIANT CIRCULATOR HEATER

Ralph E. Kruck, Clinton, Conn., assignor to Florence Stove Company, Gardner, Mass., a corporation of Massachusetts

Application June 14, 1950, Serial No. 10,513

Term of patent 7 years

(Cl. D81—10)

To all whom it may concern:

Be it known that I, Ralph E. Kruck, a citizen of the United States, and residing at Clinton, in the county of Middlesex, State of Connecticut, have invented a new, original, and ornamental Design for a Radiant Circulator Heater, of which the following is the specification, reference being made to the accompanying drawing, forming a part thereof.

The figure is a front perspective view of a radiant circulator heater, taken slightly from above and to the left embodying my new design.

The right side of the radiant circulator heater is substantially like the left side.

I claim:

The ornamental design for a radiant circulator heater, as shown and described.

RALPH E. KRUCK.
